UNITED STATES PATENT OFFICE.

GOODWIN B. SMITH, OF PHILADELPHIA, PENNSYLVANIA.

NURSING-VEST.

1,136,727.

Specification of Letters Patent.

Patented Apr. 20, 1915.

Application filed June 17, 1914. Serial No. 845,665.

To all whom it may concern:

Be it known that I, GOODWIN B. SMITH, a citizen of the United States, residing at Philadelphia, in the county of Philadelphia and State of Pennsylvania, have invented 5 certain new and useful Improvements in Nursing-Vests; and I do hereby declare the following to be a full, clear, and exact description of the invention, such as will enable others skilled in the art to which it 10 pertains to make and use the same.

This invention relates to certain novel and useful improvements in nursing vests and similar articles of apparel.

15 In carrying out my invention it is my purpose to provide a vest of this character adapted to be worn by nursing mothers, and which in addition to facilitating the nursing operation is designed also to perform the 20 functions of a bust or breast support.

Another object of the invention is the provision of a nursing vest which may be conveniently and comfortably worn beneath the ordinary shirt waist or other upper 25 garment, and which when desired may be readily manipulated to permit nursing.

I also propose to provide a vest of this type which is made of such material and so constructed that the mother's garments are 30 protected during the nursing operation, as well as between the times of nursing, so that the rapid destruction of such garments due to soiling is avoided and the cost of replacing the ruined clothing is obviated.

35 Further it is my intention to provide a nursing vest having bust openings therein which are adapted to be closed by shields or flaps, these shields or flaps having pockets designed to removably receive suitable pads 40 or pieces of absorbent material for the purpose of absorbing any moisture or fluid which may drop thereon.

Furthermore I propose to provide a nursing vest which will also perform the functions of a bust supporter to hold the breasts in the natural position, thereby conducing to the comfort and appearance of the person.

With the above recited objects or others 50 of a similar nature in view, my invention consists in the construction, combination and arrangement of parts as herein set forth and falling within the scope of the appended claims.

55 In the accompanying drawings: Figure 1 is a perspective view of a combined nursing

vest and bust supporter embodying my invention, one of the flaps or shields of the vest being shown as partially open to illustrate the arrangement of the pocket for receiving the absorbent pad. Fig. 2 is a view in front elevation of the vest, both shields and flaps being shown in closed position and covering the bust openings. Fig. 3 is a rear or back view of the vest shown in Fig. 2. Fig. 4 is a vertical sectional view taken on the line 4—4 of Fig. 2.

In the present instance I have shown my invention as embodied in a nursing vest of a particular and preferred form, although I 70 wish it to be understood that it is not limited in its application to this specific form of article as certain features thereof may be advantageously employed in connection with other types of garments or articles of 75 wearing apparel, such as waists and the like.

Before entering into the detail description of my invention I will briefly state that in its preferred form it embraces among other 80 features a front body portion or section preferably of water proof fabric, having a pair of spaced bust or breast openings therein, the material of the body section above each breast opening having a piece of elastic webbing inserted for the purpose of allowing the upper portion of the vest to adjust itself to the wearer. The material of the body section below each opening is cut-away to form short vertical slits which communicate with the breast or bust openings and terminate at substantially the bottom edge or binding of the body section, these webs and slits insuring the ready adjustment of the vest when it is desired to nurse 95 the infant.

Stitched to the bottom edge of the body section at the front thereof are flaps or shields adapted to cover the breast or bust openings, these shields or flaps being fastened in their closed position over the openings by means of snap fasteners or other suitable devices. Each of these flaps or shields is also preferably formed of water proof material, and each flap has attached 105 to its inner face at the edges a short piece of gauze or net fabric, the upper edge of the fabric being separated from the upper edge of the flap or shield to form a pocket which is adapted to receive a pad of absorbent material. To one end of the body section is attached an elastic band, while the free end 110

of the band is adapted to be connected to the opposite end of the body section by a ball and socket fastener or other device, the elastic band passing around the back of the 5 wearer and securing the garment in position.

Referring now to the accompanying drawings in detail the letter A designates the body section of the vest which also forms 10 the front of the latter, this body section being preferably composed of a light, thin waterproof fabric. This section A is provided with the bust or breast openings 1, suitably spaced apart by the intervening 15 web 2. The material of the body section below each opening is slitted, as at 3, these slits extending from the opening to the bottom edge of the body section. Likewise above each breast opening the material is 20 cut-away, as at 4, for the insertion of short connecting webs 5 of elastic material, these elastic webs and the bottom slits 3 permitting the vest to readily accommodate itself to the breast of the wearer especially during 25 the nursing operation. The bottom edge of the body section is provided with a binding strip 6, while the top edge has a similar binding strip 7. Likewise each breast opening 1 is edged with a binding strip 8, while 30 the bottom slits 3 are edged with short binding strips 9, and the elastic webs 5 are edged with short binding strips 10.

To the end 11 of the body section A is 35 stitched or otherwise attached a strip of elastic webbing 12, provided at its free end with the ball members 13 of a ball and socket fastener of any well known type, the socket members 14 of this ball and socket fastener being attached to the opposite end 40 15 of the body section of the vest. It will be of course understood that any suitable means may be employed for securing the ends of the body section in order to fasten the vest upon the wearer.

Secured to the lower edge of the body section A, as at 16, are the shields or flaps 17, which are intended to cover the breast openings, and as the shields and flaps are counter-parts, a description of one will suffice for 50 both. These shields or flaps are secured to the body section at their lower or bottom edges by stitching or otherwise so that they may be opened outward and downward during the nursing operation. Such shields or 55 flaps are preferably formed of the same material as the body section A, that is of light water proof fabric. The shields or flaps are preferably approximately semi-circular in shape and have their upper edges 60 extended slightly above the upper edge of the body section A, but it will be of course understood that these flaps or shields may be of any suitable shape.

To the back of each flap or shield is 65 attached a section or piece of gauze or net

fabric 18, the edge binding 19 of the flap or shield being stitched over the edges of both flaps or shields and the piece of net fabric. The latter is attached or stitched at its side and lower edges, but is unattached at its 70 upper edge 20 so that a pocket 21 is formed into which is designed to be inserted a pad or piece of absorbent material, such as cotton or the like shown 22. Each flap or shield is provided with socket members 23 75 adapted to receive the ball members 24 secured to the body section A adjacent the top edge thereof.

From the above description taken in connection with the accompanying drawings 80 the construction and manner of using my invention will be readily apparent. The vest is secured in position on the wearer by means of an elastic back strap, and the shields or flaps are closed as shown in Fig. 2 and overlie and cover the breasts, the pad of absorbent material having been placed in the pockets 21 of these flaps or shields.

When it is desired to nurse the infant one of the flaps is opened either partially or 90 entirely and thrown outward and downward. This brings the gauze or net side of the back uppermost and the infant is then placed in position for nursing. Any moisture resulting from nursing will fall upon the gauze or net side and pass through the interstices thereof and be absorbed by the pad in the pocket. At the same time the flap will act as a protector for the other body garments which the mother may be 95 wearing. Any time one pad has been soiled it may be readily removed from the pocket and another pad substituted.

It will be noted that the entire vest is so 100 constructed that it will fit snugly in position and may be worn without discomfort or inconvenience at all times. When the flaps are closed, as shown in Fig. 2, the vest forms a supporter for the breasts, retaining the same in the natural position adding to the 110 appearance of the person and in fact fulfills all the functions of the ordinary bust supporter.

Another advantage incident to my invention is that when one of the vests has become 115 soiled it may be readily washed or cleaned, and as the pockets may be opened outward and downward the absorbent pad may be readily removed and the entire device washed in the manner of an ordinary garment. Furthermore the body section and the flap being made of water proof fabric will prevent perspiration and moisture from soiling the shirt waist or other upper garment.

While I have herein shown and described one particular embodiment of my invention, I wish it to be understood that I do not limit myself to all of the precise details herein set forth by way of illustration, as modifica- 130

tion and variation may be made without departing from the spirit of the invention or exceeding the scope of the appended claims.

5. What is claimed is:—

1. The combination with a body section having two spaced openings located entirely within and surrounded by the material constituting the body section and means for fastening the body section on the wearer, of flaps permanently attached at their lower edges to the body section below the openings, each flap being adapted to be folded downward to expose the adjacent opening and to be folded up over the opening to close the latter, and means for detachably fastening the flaps to the body section at points above the lower edges of the flaps to detachably secure such flaps in closed position.
10. 2. In an article of the class described, the combination with a body section having two spaced openings therein and means for fastening the body section on the wearer, of elastic strips inserted in the body section between the top portions of the openings and the top edge of the body section and flaps for the openings attached at their lower edge portions to the body section below the openings and adapted to be folded down to expose the openings and to be folded up over the openings to close the latter, and means for fastening the flaps in their closed position.
15. 3. The combination with a body section having two separate bust openings therein and a web between the openings, of a flap for each opening secured to the body section, the adjacent edges of the flaps being adapted when in closed position to overlap and to overlie the web between the openings, means for fastening together the overlapping portions of the flaps, and means for fastening the flaps in their closed positions.
20. 4. The combination with a body section having two relatively large spaced breast openings therein adapted to accommodate the breasts of the wearer and means for fastening the body section upon the wearer, of a flap for each opening attached to the body

section at a point below the opening and 50 adapted to be folded downward to expose the opening and to be folded up over the opening to close the latter, means for fastening each flap in its closed position, and a piece of material connected with each flap 55 and lying adjacent the inner side of such flap to form a pad receiving pocket in conjunction with the flap.

5. The combination with a body section having two relatively large bust openings 60 therein with a spacing web therebetween, of an elastic strip inserted in the body section between the top of each opening and the top edge of the body section, the material of the body section between the bottom of each bust opening and the lower edge of the body section being slitted, flaps for the bust opening permanently attached at their lower edges to the body section below the openings, each flap being adapted to be folded up over 70 the adjacent opening to close the latter, a piece of fabric attached to the inner side of each flap and forming a pad receiving pocket in conjunction with the flap, and means for securing the body section on the 75 wearer.

6. The combination with a body section having bust openings therein, the material of the body section above each bust opening including a section of elastic webbing, the 80 material of the body section below each opening being slitted, with the slits communicating with the opening, a flap for each bust opening attached at its lower portion to the lower portion of the body section and 85 adapted when closed to cover the adjacent bust opening, a piece of net material attached to each flap, and lying adjacent the inner side of the flap to form a pad receiving pocket, and means for securing the body 90 section on the wearer.

In testimony whereof, I affix my signature, in the presence of two witnesses:

GOODWIN B. SMITH.
